UNITED STATES PATENT OFFICE.

ALEXANDER HEPKE AND KURT DIENER, OF BERLIN, GERMANY.

MULTIPLE FUSE-PLUG.

No. 823,044.

Specification of Letters Patent.

Patented June 12, 1906.

Application filed February 16, 1905. Serial No. 245,900.

To all whom it may concern:

Be it known that we, ALEXANDER HEPKE and KURT DIENER, both subjects of the King of Prussia, German Emperor, and residents of Berlin, Kingdom of Prussia, German Empire, have jointly invented certain new and useful Improvements in Multiple Fuse-Plugs, of which the following is an exact specification.

Our invention relates to improvements in electric multiple fuse-plugs, and more especially to fuse-plugs provided with a current-taking-up contact-piece and a current-leading-off contact-piece, both said contact-pieces being secured to fuse-wires. As hitherto usual, these members referred to are carried by a movable fuse-carrier and a special switching member or conductor was necessary to engage one of the above-mentioned current-leading contact-pieces when the fuse-carrier is moved in relation to the base-carrying the fuse-carrier.

The employment of a special switching member and the arrangement of the fuse-wires in a fuse-carrier movable in relation to its base have given rise to many inconveniences, and therefore we have dispensed with the switching member and the movable fuse-carrier.

According to our invention we have mounted the fuse-wires stationary within the plug-body and we have provided a current-taking-up contact-body movable in relation to the plug-body respectively to the fuse-wires.

In order to make our invention clear, reference is made to the accompanying drawings, in which—

Figure 1 is a vertical cross-section on line A B of Fig. 2 of a convenient form of our improved fuse-plug. Fig. 2 is a top plan view of Fig. 1, the upper cover being removed. Fig. 3 is a horizontal cross-section on line C D of Fig. 1, and Fig. 4 is a top plan view of the current-taking-up element.

In Fig. 1, *d* is the plug-body proper, consisting of insulating material, such as porcelain and the like. The plug-body is provided with chambers *e* and channels *f*, taking up the fuse-wires *a*. Outside on the plug-body *b*, serving for taking off the

current from the fuse-wires, is stationarily mounted and connected with one end of the fuse-wires, so that all the fuse-wires are in contact with this current-taking-off piece. The other ends of the fuse-wires are connected apart with small contact-pieces *e*, arranged in recesses *g* of the plug-bottom.

h is the current-taking-up contact-piece, being provided with a projection *i*, bearing against one of the contact-pieces *e* of the temporarily-used fuse-wire. This contact-piece *h* is movably arranged, thereby permitting a fuse-wire to be connected if one fuse-wire is molten.

For the purpose of applying the contact-piece *h* to the plug-body proper the latter is provided with a bore *l*, into which a fork-shaped spring *k* projects, secured to the contact-piece *h* by means of a screw.

The operation of our improved multiple fuse-plug is most simple. Supposing that one fuse-plug is molten and we intend to connect the following fuse-wire, there is only the necessity of screwing out the plug-body from its base or socket and of displacing the contact-piece *h* from one contact-piece *e* to the next contact-piece *e* and then of screwing in again the plug-body by means of the screw-ring into its base. By arranging the contact-pieces *e* within recesses in the plug-bottom, into which also the projection *i* of the contact-piece *h* projects, the latter is prevented from being displaced if the plug-body is screwed in its socket.

The channels *e* of the plug are closed at their lower ends by any convenient material and the whole plug is filled with sand, emery, and the like and then closed at its upper end by a cap *u*. The filling up of the plug prevents any detrimental effect of the vapors and heat developed by the melting fuses.

Having thus fully described the nature of our invention, what we desire to secure by Letters Patent of the United States is—

A multiple fuse-plug comprising in combination the fuse-plug proper, a thread-ring fixed to said plug-body, fuse-wires each having one end connected to said thread-ring, contact-pieces connected to the other ends of the fuse-wires and insulated from each other, 100

a current-taking-up contact-piece, movable in relation to the fuse-wires, a projection on said current-taking-up piece and bearing against the temporarily-used fuse-wire, a
5 fork-shaped spring secured to said movable contact-piece and engaging with a hole in the plug-body, for the purpose set forth.

In witness whereof we have hereunto set our hands in the presence of two witnesses.

ALEXANDER HEPKE.
KURT DIENER.
